US00D994648S

(12) **United States Design Patent** (10) **Patent No.:** **US D994,648 S**
(45) **Date of Patent:** **** Aug. 8, 2023**

(54) **MICROPHONE WINDSCREEN**

(71) Applicant: **Logitech Europe S.A.**, Lausanne (CH)
(72) Inventors: **James Edward Renwick**, Portland, OR (US); **Branko Lukic**, Emerald Hills, CA (US); **Homin Lee**, Glendale, CA (US); **Tzyy-Woei Richard Sung**, Los Angeles, CA (US); **Adam Kirk Bennett**, Ventura, CA (US)

(73) Assignee: **Logitech Europe S.A.**, Lausanne (CH)

(**) Term: **15 Years**

(21) Appl. No.: **29/817,282**

(22) Filed: **Nov. 30, 2021**

(51) LOC (14) Cl. **14-01**

(52) U.S. Cl.

USPC **D14/225**
